LAUNDRY WASHER

Harold L. Belding, Dorchester, Mass., assignor to
 Henrici Laundry Machinery Company, Boston,
 Mass., a corporation of Massachusetts

Application October 26, 1939, Serial No. 301,393

16 Claims.

(Cl. 68—27)

This invention relates to an improvement in laundry washers and more particularly to a further development of the type of washer shown in my copending application Serial No. 224,721, filed

5 August 13, 1938.

Such a washer includes a perforate drum mounted for rotation in a housing, the articles to be washed being placed in the drum and the housing containing water which enters the drum 10 through the perforations in the walls thereof. The direction of rotation of the drum is usually changed several times during the washing treatment. As the result of the rotation the water in the housing is moved peripherally of the drum 15 and transversely of the housing, first in one direction and then in the opposite direction.

This peripheral movement of the water is made up of two components, thus the water in contact with and closely adjacent to the wall of 20 the drum travels in the direction of the rotation of the drum while the water below the drum and that between the ends of the drum and the ends of the housing travels in the opposite direction. Both these movements of the water are trans- 25 versely of the housing.

The primary object of this invention is to impart to the water a movement longitudinally of the housing in addition to that peripherally thereof by providing deflectors or baffles which impart 30 such movement. Thereby the water of the bath is uniform throughout the housing, and if desired the soap, bluing, starch and the like may be added to the water in the housing at the end or ends thereof instead of at the sides thereof as 35 is now the practice.

Various ways of equipping washers in accordance with this invention will be set forth in the following description and in the drawings which form a part thereof and in which:

40 Figs. 1 and 2 are end views, with parts broken away, of laundry washers of the type disclosed in my copending application equipped with deflectors by which this invention is carried out;

Fig. 3 is a view in side elevation, taken from 45 the right of Fig. 1 or Fig. 2, with the housing in section to expose the cylinder and deflectors;

Fig. 4 is a cross-sectional view taken along the line 4—4 of Fig. 3 of the washer shown in Fig. 1;

Fig. 5 is a sectional plan view taken along the 50 line 5—5 in Fig. 1;

Fig. 6 is a view similar to Fig. 5 of the washer shown in Fig. 2;

Figs. 7 and 8 are sectional plan and end views, respectively, of another embodiment of this invention; and

Figs. 9 and 10 illustrate in sectional plan and end views, respectively, still another embodiment of this invention.

This invention will be described as embodied in a laundry washer of the type which comprises a 5 drum 20, the walls of which are, in whole or in part, perforate, mounted for rotation in a housing 21. The drum is shown in the drawings as comprising two baskets 22 mounted end to end, each basket being adapted to contain the articles 10 to be washed. Instead of two baskets the drum may comprise a single basket or a larger number depending upon the capacity of washer desired. It will be understood that the washing of articles 15 includes not only treatment with water containing soap or other detergent, but also further and subsequent treatments, such as with water alone to rinse the goods, followed in many instances by bluing or starching treatments. For convenience, however, the term "washing" is used in the specification and claims in the generic sense to include any one or more of such treatments.

The housing 21 includes bearings 23 in which the drum 20 is supported for rotation by means (not shown). The base wall 24 of the housing 21 25 is extended to provide a reservoir 25 at one side of the drum, as set forth in the copending application mentioned above. Mounted in the reservoir 25 are baffle plates 26 which, as will be pointed out hereinbelow, serve as deflectors 30 whereby movement longitudinally of the housing is imparted to the water.

Each baffle plate 26 is associated with a basket 22 and includes a main portion 27 parallel to the basket and bent at each end to form a guiding 35 portion, the portion 28 adjacent the end of the housing being materially longer than the other portion 29. The baffle plates are spaced from the walls of the housing to define passages 30 and 31, respectively. The portions 28 of the 40 baffle plates are spaced apart to define a passage 32 which, as shown in Fig. 5, is in alignment with the space 33 between the baskets.

The movement of the water during the operation of this washer will now be described with 45 particular reference to Figs. 4 and 5. When the drum 20 is rotated clockwise (see Figs. 4 and 5) the layer of water in contact with and closely adjacent travels peripherally with the drum, while the water below that layer travels in the 50 opposite direction. For convenience the second layer is referred to as an "undertow." In Fig. 4 the arrow 35 indicates the direction of rotation of the drum and the arrows 36 indicate the directions of peripheral travel of the water. The ar- 55

rows 37 on Fig. 5 indicate the travel of the water in the spaces 38 between the ends of the drum 20 and the housing 21. Since the water in these spaces is not in contact with the peripheral surface of the drum the double movement indicated by the arrows 36 in Fig. 4 is not present. The streams of water in the spaces 38 are divided by the portions 28 of the baffles 26 into two streams 39 and 40, indicated by arrows 41 and 42, respectively, and separated by the baffle plates. The streams 39 are in part affected by the peripheral movement of the drum and in part continue to the portions 29 of the baffle plates by which they are deflected into the space 33 between the drums. The streams 40 continue along the spaces 30 until they meet at the space 32 between the baffle plates through which they flow into the space 33. In addition to the undertow movement described above, a portion of the water moved peripherally with the drum is deflected to flow along the streams 43 in the direction indicated by the arrows 44 to the spaces 38.

The movement of the water designated by the arrows 36 is caused by the peripheral rotation of the drum. The presence of the baffle plates 26 causes the water to move along the spaces 38 and 30 thus setting up a longitudinal movement of the water. The movement of the water in the streams 40 through the spaces 30 is in response to its movement in the space 33 and of necessity draws water from the spaces 38, thus setting up the movement indicated by the arrows 37.

The movement of the water described above is that set up by the rotation of the drum in the clockwise direction indicated by the arrow 35 (Fig. 4). When the drum is rotated in the counterclockwise direction (Fig. 4), however, the movement of the water will be the direct reverse of the movement just described. In other words, the water entering through space 32 will flow outwardly through the passages 30 to the passages 38.

The washer shown in Figs. 2 and 6 differs from that shown in Fig. 1 in that the base wall 24' of the housing 21' is extended at each side of the drum 20' to provide reservoirs 25', in each of which are mounted baffle plates 26'. That the rotations of the drum 20' will cause the water to flow peripherally and longitudinally of the housing in substantially the manner previously described is, it is believed, obvious, so that there is no need for a detailed description thereof.

Figs. 7 and 8 illustrate further developments of the embodiment previously described and correspond to Figs. 5 and 4, respectively. Since these developments consist in additions to the structures previously described in detail, the description of the structures will not be repeated and the same reference characters will be applied to the corresponding elements without comment. In order to guide the streams of water through the passages 30, blocks 50 have been mounted at the corners of the reservoir and a block 51 has been mounted at the mouth of the passage 32. A series of blades or paddles 52 are mounted on the drum 20 between the baskets 22 to increase the speed of travel of the water through the space 33. At the end of the space 33, opposite the block 51, is mounted a block 53 which, as is shown in the drawings, is so formed that the stream of water is separated after flowing through the space and is deflected toward the ends of the housing 20.

Figs. 9 and 10 illustrate the application of this invention to a washer of the well known cylindrical housing type. This type of washer, unlike the

other types discussed hereinbefore, does not include a reservoir. A drum 60, rotatably mounted within the housing 61, includes baskets 62. The articles to be washed are placed in the baskets of the drum which has, according to the usual custom, perforate walls. The bath water is contained in the housing and enters the lower portions of the baskets through the perforations therein (not shown). Mounted upon the lower portion of the housing at one side of the vertical plane of the axis of the drum are baffle plates 66 formed like the plates 26 with portions 67 extending longitudinally of the housing 61 and parallel to the drum 60 and bent end portions 68 and 69. The movement of the water initiated peripherally by the rotation of the drum 60 is affected by the baffle plates 66 in the manner already described in detail with respect to the baffle plates 26.

While certain embodiments of the invention have been shown and described, it will be understood that the invention is not limited to such embodiments and that it also includes such other embodiments thereof as may be made without departing from the spirit and scope of the invention set forth in the following claims.

I claim:

1. A washer comprising a stationary outer housing, and a perforate drum rotatable within the housing, the drum containing the articles to be washed and the housing containing water which enters the drum through the perforations therein and which is agitated peripherally upon the rotation of the drum, and deflector means mounted within the housing, said means being so shaped and positioned with relation to said housing and drum as to direct the peripherally agitated water longitudinally of the drum whereby a longitudinal and peripheral agitation of the water is obtained.

2. In a washer comprising a stationary outer housing, a perforate drum rotatable within the housing, and means for rotating said drum in either direction, the drum being adapted to contain articles to be washed, and the drum and housing being adapted to contain water which is agitated transversely of the housing by the rotation of the drum, deflector means including a baffle plate having its lower edge mounted in contact with the base of the housing and cooperating therewith to form a longitudinal passageway, below and at one side of the drum, said baffle plate extending longitudinally of the drum, said means being so shaped as to impart to the water so agitated a movement longitudinally of the housing, as the drum is rotated in either direction.

3. A washer comprising a rotatable perforate drum and a stationary outer housing, the drum containing the clothes to be washed and the drum and outer housing containing water, which water is agitated peripherally upon the rotation of the drum, the water adjacent the curved side wall of the drum moving in the direction of rotation of the drum, and the water below that adjacent the drum moving in the opposite direction transversely of the housing, and deflector means mounted upon the base of the housing and spaced from the end walls thereof, said means being so spaced and positioned with relation to said housing and drum as to direct the transversely moving water in a direction longitudinally of the drum whereby a longitudinal and peripheral agitation of the water in the housing is obtained.

4. In a washer comprising an outer housing, a drum rotatable within the housing and including

- a plurality of cylindrical perforate baskets joined end to end, and means for rotating said drum in either direction, the baskets being adapted to contain articles to be washed, and said housing being adapted to contain water which enters the baskets through the perforations therein and which is agitated transversely of the housing by the rotation of the drum, deflector means carried by the housing and being so shaped and positioned with respect to each basket that longitudinal movement is imparted to the water so agitated, said means being spaced apart from each other and from the ends of the housing and being effective to cause such longitudinal movement when the drum is rotated in either direction.
5. In a washer comprising an outer housing, a drum rotatable within the housing and including a plurality of cylindrical perforate baskets joined end to end, and means for rotating said drum in either direction, the baskets being adapted to contain articles to be washed, and said housing being adapted to contain water which enters the baskets through the perforations therein and which is agitated transversely of the housing by the rotation of the drum, defectors mounted upon the housing, below and at one side of the drum, each deflector being associated with a basket and including a longitudinally extending portion parallel to and approximately the same length as its basket and a transversely extending portion at one end of the first-named portion, each of said deflector means being effective by reason of its shape to cause a longitudinal movement of the water so agitated when the drum is rotated in either direction.
6. In a washer comprising an outer housing, a drum rotatable within the housing and including a plurality of cylindrical perforate baskets joined end to end, and means for rotating said drum in either direction, the baskets being adapted to contain articles to be washed, and said housing being adapted to contain water which enters the baskets through the perforations therein and which is agitated transversely of the housing by the rotation of the drum, defectors mounted upon the housing, below and at one side of the drum, each deflector being associated with a basket and including a portion spaced from the wall of the housing and defining therewith a passage through which the water so agitated flows longitudinally of and parallel to the basket associated with the deflector.
7. In a washer comprising an outer housing, a drum rotatable within the housing and including a plurality of cylindrical perforate baskets joined end to end, and means for rotating said drum in either direction, the baskets being adapted to contain articles to be washed, and said housing being adapted to contain water which enters the baskets through the perforations therein and which is agitated transversely of the housing by the rotation of the drum, defectors mounted upon the housing, below and at one side of the drum, each deflector being associated with a basket and including a portion spaced from the wall of the housing and defining therewith a passage through which the water so agitated flows longitudinally of and parallel to the basket associated with the deflector, and portions connected to the ends of the first-named portion and defining passages through which the water is guided to and from said first-named passages.
8. In a washer comprising an outer housing, a drum rotatable within the housing and includ-
- ing a plurality of cylindrical perforate baskets joined end to end, and means for rotating said drum in either direction, the baskets being adapted to contain articles to be washed, and said housing being adapted to contain water which enters the baskets through the perforations therein and which is agitated transversely of the housing by the rotation of the drum, defectors mounted upon the housing, below and at one side of the drum, each deflector being associated with a basket and including a portion spaced from the wall of the housing and defining therewith a passage through which the water so agitated flows longitudinally of and parallel to the basket associated with the deflector, and portions connected to the ends of the first-named portion, and baffles which cooperate with said portions to define passages through which the water is guided to and from said first-named passages.
9. In a washer comprising an outer housing, a drum rotatable within the housing and including a pair of cylindrical perforate baskets joined end to end, and means for rotating said drum in either direction, the baskets being adapted to contain articles to be washed and said housing being adapted to contain water which enters the baskets through the perforations therein and which is agitated transversely of the housing by the rotation of the drum, deflector means which imparts to the water so agitated a movement longitudinal of the housing, said means including spaced baffle plates mounted upon the housing below and at one side of the drum, each plate being associated with a basket and paddles carried by the drum between the baskets.
10. In a washer comprising an outer housing, a drum rotatable within the housing and including a pair of cylindrical perforate baskets joined end to end, and means for rotating said drum in either direction, the baskets being adapted to contain articles to be washed and said housing being adapted to contain water which enters the baskets through the perforations therein and which is agitated transversely of the housing by the rotation of the drum, deflector means which imparts to the water so agitated a movement longitudinal of the housing, said means including spaced baffle plates mounted upon the housing below and at one side of the drum, each plate being associated with a basket and including a longitudinally extending portion parallel to and approximately the same length as its basket, and a block at the space between the plates.
11. In a washer comprising an outer housing, a drum rotatable within the housing and including a pair of cylindrical perforate baskets joined end to end, and means for rotating said drum in either direction, the baskets being adapted to contain articles to be washed and said housing being adapted to contain water which enters the baskets through the perforations therein and which is agitated transversely of the housing by the rotation of the drum, deflector means which imparts to the water so agitated a movement longitudinal of the housing, said means including spaced baffle plates mounted upon the housing below and at one side of the drum, each plate being associated with a basket and including a longitudinally extending portion parallel to and approximately the same length as its basket, a block at the space between the plates, and paddles carried by the drum be-

tween the baskets in alignment with the space between the plates.

12. In a washer comprising an outer housing, a perforate drum rotatable within the housing, and means for rotating said drum in either direction, said drum containing the articles to be washed and said housing being adapted to contain water which enters the drum through the perforations in the wall thereof and is agitated peripherally of the drum by the rotation thereof, the base wall of the housing being spaced from the drum to form a reservoir, and deflector means mounted in the reservoir, said means including plates spaced from the wall of the housing to define open ended passages parallel to and extending longitudinally of the drum, which passages guide the so agitated water and cause it to travel longitudinally of the drum as well as peripherally thereof as the drum is rotated in either direction.

13. In a washer comprising an outer housing, a perforate drum rotatable within the housing, and means for rotating said drum in either direction, said drum containing the articles to be washed and said housing being adapted to contain water which enters the drum through the perforations in the wall thereof and is agitated peripherally of the drum by the rotation thereof, the base wall of the housing being spaced from the drum to form a reservoir, and deflector means mounted in the reservoir, said means including plates spaced from the wall of the housing to define open ended passages parallel to and extending longitudinally of the drum, which passages guide the so agitated water and cause it to travel longitudinally of the drum as well as peripherally thereof as the drum is rotated in either direction, and blocks at the ends of said passages by which the travel of the water therethrough is further guided.

14. In a washer comprising an outer housing, a perforate drum rotatable within the housing, and means for rotating said drum in either direction, said drum containing the articles to be washed and said housing being adapted to contain water which enters the drum through the perforations in the wall thereof and is agitated peripherally of the drum by the rotation thereof, the base wall of the housing being spaced from the drum to form a reservoir, and deflector means mounted in the reservoir, said means including aligned plates parallel to the drum and spaced from the wall of the housing to define passages extending longitudinally of the drum, the ends of the plates being spaced from the ends of the housing, and from one another to define passages connected with said first-named passages, whereby the water so agitated is guided through certain of said second-named passages

into said first-named passages, and along said first-named passages longitudinally of the drum to the other of said second-named passages, by which the water is guided from said first-named passages.

15. In a washer comprising an outer housing, a perforate drum rotatable within the housing, and means for rotating said drum in either direction, said drum containing the articles to be washed and said housing being adapted to contain water which enters the drum through the perforations in the wall thereof and is agitated peripherally of the drum by the rotation thereof, the base wall of the housing being spaced from the drum to form a reservoir, and deflector means mounted in the reservoir, said means including aligned plates parallel to the drum and spaced from the wall of the housing to define passages extending longitudinally of the drum, the ends of the plates being spaced from the ends of the housing, and from one another to define passages connected with said first-named passages, whereby the water so agitated is guided through certain of said second-named passages into said first-named passages, and along said first-named passages longitudinally of the drum to the other of said second-named passages, by which the water is guided from said first-named passages, and baffles mounted in the housing adjacent the juncture of said second-named passages with said first-named passages.

16. In a washer comprising an outer housing, a perforate drum rotatable within the housing, and means for rotating said drum in either direction, said drum containing the articles to be washed and said housing being adapted to contain water which enters the drum through the perforations in the wall thereof and is agitated peripherally of the drum by the rotation thereof, the base of the housing being spaced from the drum to form a reservoir, and deflector means mounted in the reservoir, said means including aligned plates parallel to the drum and spaced from the wall of the housing to define passages extending longitudinally of the drum, the ends of said plates being bent away from that wall of the housing and spaced from the ends of the housing and from each other to define passages connected with the first-named passages, whereby, when the drum is rotated in the direction away from the deflector means, the water agitated thereby is guided by the passages between the ends of the plates and the ends of the housing to said first-named passages, along which it travels longitudinally of the drum to the passage defined by the ends of the plate by which it is guided from the first-named passages.

HAROLD L. BELDING.
